UNITED STATES PATENT OFFICE.

LOUIS STEINBERGER, OF NEW YORK, N. Y.

INSULATOR-SUPPORT.

SPECIFICATION forming part of Letters Patent No. 783,230, dated February 21, 1905.

Application filed May 11, 1903. Serial No. 156,520.

To all whom it may concern:

Be it known that I, LOUIS STEINBERGER, a citizen of the United States, and a resident of the city of New York, borough of Brooklyn, 5 in the county of Kings and State of New York, have invented a new and Improved Insulator-Support, of which the following is a full, clear, and exact description.

My invention relates to insulator-supports 10 and admits of general use, but is more particularly adapted for use with a type of insulator employed for supporting outdoor wires which are exposed to the action of the weather.

The several purposes of my invention are 15 stated in the following specification and pointed out in the appended claims.

Reference is to be had to the accompanying drawings, forming a part of this specification, in which similar characters of reference indicate corresponding parts in both figures.

Figure 1 is a front elevation of a cross-beam, upon which my insulator-support is mounted, the insulator-support being partly shown in section; and Fig. 2 is a fragmentary central 25 section through the lower part of the insulator-support.

A cross-beam is shown at 1. Mounted upon this cross-beam is a metallic stem 2, provided with a shoulder 3 and with a threaded portion 30 4. Mounted upon the threaded portion 4 is a revolute nut 5, which is locked in position by means of a second nut 6. The metallic stem 2 is provided with a reduced portion 7, having a thread 8. Revolubly mounted upon 35 the threaded portion just mentioned is a threaded metallic sleeve 9, provided with a depending skirt 10, having a peripheral flange 11 of the shape indicated. The sleeve 9, the skirt 10, and the flange 11 are of course integral with each other and constitute a hollow metallic member having a general frusto-conical shape, as indicated in Fig. 1, and are used for the purpose of strengthening an envelop 12, mounted upon said hollow member. The 40 envelop 12 is of insulating material and has the general form of a cone-frustum and is provided with threads 13 and with a weather-shield 14 of the shape indicated. An endless recess 15 completely encircles the insulation 45 and at 16 is disposed comparatively near the

cross-beam 1. The purpose of this recess is to guide falling elements—such as rain, snow, dust, &c.—downwardly to the comparatively low point 16, thus leading them away from the vital parts of the mechanism and enabling 55 them to flow off easily in a lateral direction, so that the channel will lead the flow of water beyond the sides of the cross-arm, thereby preserving the pins from moisture and reducing the chances for arcing of the current. 6c The threads 13 are provided for the purpose of supporting the insulator, which may be of any preferred form.

When the device is mounted as indicated in Fig. 1, any rain, snow, or sleet which may 65 fall within the recess 15 is guided off and escapes at 16. The cross-beam 1 is thus protected from the action of the water, sleet, &c.

I do not limit myself to the particular form of stem shown. Neither am I limited to the 70 particular arrangement of the insulating member relatively to the cross-arm nor to the exact form of the skirt as shown. It is obvious that persons skilled in the art may without departing from the spirit of my invention construct the parts mentioned in many other forms.

Having thus described my invention, I claim as new and desire to secure by Letters Patent —

1. An insulator-support, comprising a stem 80 provided with a threaded portion, a metallic sleeve disposed concentric to said stem and provided with a threaded portion engaging said threaded portion of said stem and also with a skirt, and an insulating member mounted upon said metallic sleeve and engaging said skirt, said insulating member being provided with a portion for supporting an insulator. 85

2. An insulator-support, comprising a stem 90 provided with a thread, a metallic sleeve mounted upon said stem and provided with a thread engaging said thread thereof, said sleeve being further provided with a skirt, and a member of insulating material encircling said sleeve and provided with a spout for directing the flow of moisture. 95

3. An insulator-support, comprising a stem provided with a threaded portion, a metallic sleeve provided with a threaded portion engaging said threaded portion of said stem and 100

- also provided with a skirt, said skirt depending from said stem, and a member of insulating material encircling said sleeve and extending below the lower extremity thereof, said 5 member of insulating material being provided with a spout.
4. An insulator-support, comprising a stem provided with a thread, a metallic sleeve mounted upon said stem and provided with a thread engaging said thread thereof, said 10 sleeve being further provided with a skirt, and a member connected exteriorly with said sleeve and provided at its lower end with a gutter for directing the flow of moisture.
5. An insulator-support, comprising a stem provided with a threaded portion, a metallic 15 sleeve provided with a threaded portion engaging said threaded portion of said stem and also provided with a skirt, said skirt depending from said stem, and a member connected exteriorly with said sleeve and extending below the lower extremity thereof, said member being provided with a portion for directing 20 the flow of moisture.
6. An insulator-support, comprising a stem, a metallic member mounted thereon, and a member of insulating material mounted upon 25 said metallic member, said member of insulating material being closed at its upper end and provided at its lower end with a spout and with portions raised higher than said spout for the purpose of directing the flow of moisture 30 thereinto.
7. An insulator-support, comprising a stem provided with a thread, a metallic sleeve closed 35 at one end and provided with a thread mating said thread of said stem, and a hollow member mounted upon said metallic member said hollow member having a portion formed into 40 a spout and also having a portion raised relatively to the level of said spout for the purpose of directing moisture thereinto, said members also having a closed upper end encircling the upper end of said stem.
8. As an article of manufacture, an insulator-support comprising a hollow member of insulating material provided at its base with a water-shedding course, said course having 45 raised side walls for directing the flow of water, and a hollow strengthening member en-

gaging said member of insulating material and provided with a threaded portion for engaging a supporting-pin.

9. An insulator-support, comprising a hollow member of insulating material provided at 55 its base with a water-shedding course, said course having side walls elevated above said base for directing the flow of water, and a hollow metallic member for strengthening said hollow member of insulating material.

10. An insulator-support, comprising a hollow member of insulating material provided with a base, and with side walls integral therewith and raised above the normal surface thereof for directing the flow of water, said member of insulating material being further provided with a hollow metallic member secured immovable thereto for strengthening the 60 same.

11. In an insulator-support, the combination of a hollow member of insulating material provided at its base with a surface having walls raised relatively thereto for directing the flow of water, a hollow metallic lining for said hollow member, and mechanism connected with said hollow metallic lining for detachably mounting the same.

12. An insulator-support, comprising a member of insulating material provided at its base with a water-shedding course, said course 80 having side walls elevated above said base for directing the flow of water, and a metallic support for strengthening said member of insulating material.

13. In an insulator-support, the combination of a member of insulating material provided with a base, and with side walls integral with said base and raised above the normal surface thereof for directing the flow of water, and a metallic member for strengthening and mounting the said member of insulating material.

In testimony whereof I have signed my name to this specification in the presence of two subscribing witnesses.

LOUIS STEINBERGER.
